LEWIS CONDICT BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

FRONT HEAD FOR ROCK-DRILLS.

1,393,072.

Specification of Letters Patent. Patented Oct. 11, 1921.

Application filed July 6, 1920. Serial No. 394,193.

To all whom it may concern:

Be it known that I, LEWIS C. BAYLES, a citizen of the United States, residing at Easton, in the county of Northampton, State 5 of Pennsylvania, have invented a certain new and useful Improvement in Front Heads for Rock-Drills, of which the following is a specification.

This invention relates to a removable 10 front head for rock drills of the hammer type, in which a renewable bushing is ordinarily inserted in the bore of the front head, through which the shank of the drill steel is adapted to extend into position to receive 15 the impact blow of the hammer.

In spite of every reasonable precaution, and the skill of the best blacksmiths, a drill steel will occasionally be furnished to the 20 drill operators having a relatively soft shank, which will swell or become upset at the end being struck by the hammer, so that it becomes impossible to withdraw the steel axially or longitudinally through the chuck or bushing in the head. Under such circumstances, whether the miner is using a 25 rock drill having a solid front head or a bushed front head, it becomes necessary to remove a portion of the front of the rock drill, lay the drill steel on a piece of track 30 or other support to form an anvil, and pound the upset portion of the shank until the end is small enough to pass through the solid front head or the bushing, as the case may be, after which the machine is reassembled 35 and the work is continued. The operation described is troublesome and vexatious even with a hexagon shank, but particularly difficult with a cruciform shank and in any case much valuable time is lost.

40 The primary object of the present invention, is to overcome the difficulty of removing an upset drill steel from the bushing in the front head by an improved front head construction having a split bushing which 45 may be removed from the drill steel after the steel and bushing have been removed from the front head. Another steel may then be inserted in the machine and the work continued.

50 Another object of the invention is to construct the split bushing in such manner that it will sustain and afford resistance to side thrust without, however, weakening the front head.

55 To these and other ends, the invention con-

sists of the preferred construction of front head shown in the accompanying drawings, in which,

Figure 1 is a side elevation of a stoping 60 drill selected to illustrate the invention;

Fig. 2 is an enlarged transverse sectional view through the front head on the line 2-2 of Fig. 1 looking in the direction of the arrows;

Fig. 3 is a longitudinal sectional view 65 through the front head on the line 3-3 of Fig. 2 looking in the direction of the arrows, and

Fig. 4 is a detail perspective view showing the two parts of a split bushing lying 70 side by side before assembly.

Referring to the drawings, Fig. 1 represents a stoping drill having the hammer cylinder A to which a front head B is removably connected in the usual manner as 75 by means of the side bolts C. The rock drill is also provided with the usual feed cylinder D and other operative parts which it is not necessary to mention or describe as they form no part of the present invention. A drill steel E, in this instance of hexagonal form, has been chosen by way of example to illustrate the invention.

The front head B is provided with a bore F adapted to receive a renewable bushing 85 illustrated in detail in Fig. 4, having a uniform bore through which the shank of the drill steel E is adapted to extend into position to receive the impact blow delivered by the hammer on the anvil block G, as 90 illustrated in Fig. 3.

This bushing is preferably formed from a hollow cylindrical sleeve having the metal of its walls at diametrically opposite points weakened and then split apart along longitudinal lines to form two substantially symmetrical sections adapted to fit together along the roughened split surfaces H and remain firmly in contact when the shank of the drill steel E is inserted in the said bushing.

One suitable method of splitting the cylindrical sleeve to form the two portions J and K of the bushing, is to cut or otherwise form longitudinal grooves in the walls 105 of the sleeve as illustrated at L to a sufficient depth to permit the sleeve to be split apart by a wedge or other means. The walls of the bushing are thus partially cut and partially split or broken along the lines of 110

- cleavage and the roughened split surfaces are preferably left untouched so that the two halves of the bushing will fit tightly together within the bore of the front head.
- 5 The bushing formed of the two parts J and K, although split apart, affords resistance to side thrust of the drill steel without weakening the front head, and a drill steel, which has become upset at the end O and
- 10 cannot be withdrawn axially through the bushing, may be removed from the bushing by separating the two sections J and K after removal from the front head.

The front head B may be of the usual form having a longitudinal split or opening P along one side. The split bushing J, K, is preferably inserted into the front head up to the shoulder R and suitable means are provided for holding the bushing in the bore 20 of the front head. In this instance the transverse locking bolt S having the nuts T and the wedge-shaped body portion U serves to hold the sections of the bushing in position by engagement with the notches 25 V on each section.

Obviously, the construction may be modified without departing from the invention as described and claimed herein and I am not to be understood as limiting the invention 30 to the details shown in the drawings which illustrate one preferred embodiment.

I claim:

1. A front head construction for a rock drill of the hammer type, said front head 35 provided with a bore adapted to receive a renewable bushing having a uniform bore through which the shank of the drill steel is adapted to extend, said bushing being

formed from a hollow cylindrical sleeve having the metal of its walls at diametrically opposite points weakened and split apart along longitudinal lines to form two substantially symmetrical sections adapted to fit together along the roughened split surfaces and remain firmly in contact when the shank of a drill steel is inserted in the said split bushing, and means for holding said split bushing in the bore of the front head, whereby the bushing affords resistance to side thrust and permits removal of a drill 50 steel which has been upset at the end.

2. A front head construction for a rock drill of the hammer type, said front head provided with a bore adapted to receive a renewable bushing having a uniform bore 55 through which the shank of the drill steel is adapted to extend, said bushing being formed from a hollow cylindrical sleeve having the metal of its walls at diametrically opposite points weakened and split apart along longitudinal lines to form two substantially symmetrical sections adapted to fit together along the roughened split surfaces and remain firmly in contact when the shank of a drill steel is inserted in the said split 60 bushing, and a locking bolt extending transversely through the wall of the front head and engaging notches in both of said bushing sections for holding said bushing sections in the front head, whereby the bushing affords resistance to side thrust and permits removal of a drill steel which has become upset at the end.

In testimony whereof I have signed this specification.

LEWIS CONDICT BAYLES.
